his Atty.

UNITED STATES PATENT OFFICE.

PAUL S. KNITTEL, OF ST. LOUIS, MISSOURI, ASSIGNOR TO AMERICAN PULVERIZER COMPANY, OF ST. LOUIS, MISSOURI, A CORPORATION OF MISSOURI.

PULVERIZER.

1,424,923.

Specification of Letters Patent. Patented Aug. 8, 1922.

Application filed January 2, 1919. Serial No. 269,328.

To all whom it may concern:

Be it known that I, PAUL S. KNITTEL, residing in the city of St. Louis and State of Missouri, have invented a new and useful 5 Improvement in Pulverizers, of which the following is a specification.

This invention relates to grate bars, especially to bars intended for use in connection with pulverizers wherein the ends of the 10 grate bars are supported in the side walls of the pulverizer in close proximity to the hammers carried by the rotor.

The principal object of the present invention is to make provision for varying the 15 spacing of grate bars.

The invention consists in a grate bar having spacing lugs projecting from its opposite sides so arranged that when a series of such bars are placed side by side in one position, one spacing is obtained and when one of such bars is turned end for end a different spacing is obtained; and it further consists in the arrangements and combinations of parts hereinafter described and claimed.

25 In the accompanying drawings, wherein like symbols refer to like parts wherever they occur,

Fig. 1 is a vertical cross-section taken through the lower portion of a pulverizer 30 showing a number of grate bars embodying my invention arranged therein, the bars being shown in cross-section on the line 1—1 in Fig. 2;

Fig. 2 is a longitudinal section taken 35 through the pulverizer on the line 2—2 in Fig. 1;

Fig. 3 is a plan view of a number of grate bars showing the grate bars arranged with their lugs opposite each other to obtain the 40 wide spacing;

Fig. 4 is a plan view of the bars so positioned so as to obtain the narrow spacing; and

Fig. 5 is a view similer to Fig. 4 showing 45 a modified form of grate bar.

My invention is shown in connection with a pulverizer. As shown in Figs. 1 and 2 of the drawing, the side walls of the lower casing 5 of the pulverizer are each provided 50 with an inwardly projecting arcuate flange 6 upon which the grate bars 7 are supported to form an arcuate grate. The grate bars are substantially T-shape in cross-section and comprise a stem portion 8 whose thick-

ness increases from the bottom towards the 55 top, and a head portion 9 of rectangular section. The stem portion 8 of the bar diminishes in depth from the middle toward each end, and the bars are provided with bearing ends 10, which rest on the arcuate flanges 6 60 of the side walls of the lower casing 5.

Each of the grate bars is provided with spacing lugs 11 on its opposite sides, which are flush with the upper surface of the head portion 9 of the bar and have wide flat faces.

65 The lugs on one side of the bar are located at equal distances from the middle part or mid-line of the bar, and the lugs on the other side of the bar are also located at equal distances from the mid-line, but are offset 70 longitudinally of the bar from its middle towards each end with respect to the lugs on the opposite side.

With the bars arranged side by side in the same position, (as shown in Fig. 4) the bars are spaced apart 75 the thickness of the lugs, the offsetting of the lugs causing the lugs on one bar to clear those on the other. On the other hand, when one of the bars is turned end for end with respect to its neighbor (as shown in Fig. 3) 80 the wide flat faces of their lugs abut against each other and thus the spacing of the bars is the sum of the thicknesses of the meeting lugs. The opposite sides of the lower portion of the stem 8 of the bars are provided with lugs 12 which are disposed directly below the lugs 11 at the middle portion of the bar.

85 These lugs 12 space the lower portions of the bars which have a tendency to tilt when the bars reach a position on either side of the arcuate supporting flange 6 of the side walls of the lower casing 5. When the bars are arranged in a horizontal line, as when they are used in connection with furnaces, these lugs 12 may be eliminated.

90 By placing the bars in the position shown in Fig. 3 with the lugs of the adjacent bars registering, the wide spacing can be obtained. By turning alternate bars end for end and placing them in the position shown in Fig. 4, with the lugs of one bar bearing 95 against the body portion of the adjacent bar, the narrow spacing shown can be obtained.

100 With a set of bars of the kind described having lugs projecting the same distance from the sides, two different widths of spacing can be obtained, but it is obvious that 105 with sets of bars wherein the several bars

having spacing lugs which project different distances from their sides, various widths of spacing can be obtained.

As shown in Fig. 5, two widths of spacing can also be obtained with two sets or styles of grate bars A and B, bar A having the lug adjacent to the right of the center line eliminated and bar B having the lug adjacent to the left of the center line eliminated. 10 These two types of bar are necessary to obtain the wide spacing, but to obtain the narrow spacing, one or the other or both types of bar may be used.

The hereinbefore described bar is self-spacing, can be quickly placed in position and when worn or damaged can be easily replaced. Due to the shape of the head portion 9 at the top of said bar the life of said bar is longer than the bar of the type 20 heretofore used. The head portion 9 of the bar is rectangular in cross-section and therefore less apt to wear at the corners, which are right angles, than the bars of the ordinary type which is V-shaped in cross-section 25 and has sharp angles at its upper corners.

What I claim is:

1. A pulverizer having an arcuate grate comprising separate grate bars, each grate bar consisting of a vertical stem portion 30 having a head portion at the top thereof, said grate bar having spacing lugs on its opposite sides provided with flat end faces, some of the lugs on one side of the bar being disposed in pairs at equal distances from a 35 line midway of the length of the bar, and some of the lugs on the other side also being disposed in pairs at equal distances from said midway point and the lugs on one side being offset longitudinally of the bar with 40 respect to the lugs on the opposite side of said bar, whereby when said bar is placed along side of a similar bar with the lugs of said bars registering, one width of spacing is obtained and, when said bar is turned end 45 for end the lugs of said bars are out of register and a different width of spacing is obtained.

2. A pulverizer having an arcuate grate comprising separate grate bars, each grate 50 bar consisting of a vertical stem portion having a rectangular head, said grate bar having bearing portions at its opposite ends, one side of said bar having bearing lugs at each end and a lug on each side of its middle 55 part spaced equidistant therefrom, the other side of said bar having a lug located

at its middle part and having a lug near each end spaced equidistant from said middle part and offset inwardly from each end of the bar with respect to the end lug on 60 said first mentioned side, whereby when said bar is placed along side of a similar bar with the lugs of said bars registering, one width of spacing is obtained and, when said bar is turned end for end the lugs of said bars are 65 out of register and a different width of spacing is obtained.

3. A pulverizer having an arcuate grate comprising separate grate bars, each grate bar consisting of a vertical stem portion 70 having a head portion of substantially rectangular section, said grate bar having bearing portions at its opposite ends, one side of said grate bar having spacing lugs at each end and a spacing lug at the top and bottom 75 of said side located on each side of the middle part of the bar and spaced equidistant therefrom, the other side of said bar having lugs at the top and bottom thereof located at the middle part of the bar and 80 having a lug near each end spaced equidistant from the middle part of said bar and offset inwardly from each end of the bar with respect to the end lugs on said first mentioned side. 85

4. A pulverizer having an arcuate grate comprising separate grate bars, each grate bar having spacing lugs on opposite sides offset longitudinally of the bar, the lugs on one side being so positioned as to be out of 90 register with the lugs of a similar bar alongside thereof and in register with the lugs of said bar when it is turned end for end with its ends flush with the ends of the other bar.

5. A pulverizer having an arcuate grate 95 comprising a series of grate bars arranged side by side, each of said grate bars having spacing lugs on both sides, the lugs on one side of said bar being offset longitudinally 100 of the bar from its middle towards each end with respect to the lugs on the opposite side of said bar, whereby, with the bars placed side by side in the same position, their lugs register and one width of spacing is obtained and, with every other one of said 105 bars turned end for end, the lugs of adjacent bars are out of register and a different width of spacing is obtained.

Signed at St. Louis, Missouri, this 28th day of December, 1918.

PAUL S. KNITTEL.
